UNITED STATES PATENT OFFICE.

ERNEST B. THURSTON, OF TOLEDO, OHIO, ASSIGNOR TO THE HAUGHTON ELEVATOR & MACHINE CO., OF TOLEDO, OHIO, A CORPORATION OF OHIO.

CONTROL SYSTEM FOR ELECTRIC ELEVATORS.

Application filed May 8, 1922. Serial No. 559,173.

This invention relates to features of alternating electric current elevator control and operation.

This invention has utility when incorporated in elevators wherein polyphase alternating electric current is used in connection with two speed motors and the control devices therefor.

Referring to the drawings:

10 Fig. 1 is an across-the-line diagram of a wiring lay-out embodying the invention, the reference characters in parenthesis indicating the operator for the switch adjacent which such reference character in parenthesis is placed.

15 Fig. 2 is a wiring diagram of the features thereof, the switches on the control board being in the reverse direction or as looking at the back from Fig. 1.

20 In a building structure there is herein shown as provided an elevator shaft or elevator well 1 having a plurality of landings or floors 2 past which or to which the elevator car 3 is operable in this shaft 1. This 25 elevator car in its travel is handled by cable 4 extending upward from the car 3 in the shaft 1 about drum 5 to idler 6 and then to counter weight 7. In the operation of this 30 elevator car, to shift it from landing to landing in shaft 1, there is herein provided an alternating current electric motor 8 having on its shaft 9 fly ball governor 10, brake drum 11, and worm 12. This worm 12 is in mesh with worm wheel 13 on shaft 14 carrying 35 the drum 5.

As an instance of operation it is herein shown that the car is to be shifted downward in the elevator shaft 1. To this end controller 15 may be shifted in the car so 40 that its upper portion swings to the left having its contact 16 still in connection with a terminal 17. This terminal 17 has line 18 therefrom through emergency switch 19 in the car 3, thence by line 20 through upper 45 overtravel switch 21, thence by line 22 to lower overtravel switch 23 and therefrom by line 24 to power supply line 25.

This controller 15 has remote from the 50 contact 16, contact 26 which, in the shifting of the top of the controller 15 to the left, is swung to the right but still remains on terminal 27 connected by line 28 extending about coil 29 of switch 30 and extending therefrom by line 31. This switch 30, cuts 55 out the brake releasing coil whenever the

controller 15 is thrown to center. This line 31 from the switch 30, extends through landing door interlock switches 34 and thence by line 35 to the car 3 where there is service switch 36. From this service switch 36 is line 37 to fly ball governor 38, which fly ball governor 38 is controlled by the speed of the car due to the line 39 connected to the car 3 and about pulley 40 in the top of the shaft 1 and thence about pulley 41 in the bottom of the elevator shaft. As long as the car 3 travels in the elevator shaft 1 at the rate of speed below the cut out of this fly ball governor 38, the switch at this governor remains closed and the current from the line 37 passes therethrough and thence by line 42 to the upper overtravel switch 21 thence by line 43 to the lower overtravel switch 23, thence by line 44 to power supply line 45.

In shifting this controller 15 from its neutral position for down direction travel to the left as to top or upper contact, this contact 16 is in connection with terminal 46 having line 47 through resistance 48 and line 201 to switch 200 at fly ball governor 10 on the shaft 9. At the starting position of the car, this switch 200 is normally open. From this switch 200 extend lines 202, 108, 87, 88, on the side of the direction switches to receive power from the line 25 after the direction switches are thrown. The other contact 26 has connection therefrom by terminal 71, line 70, switch 55, line 69, contact 68, line 67, resistance 66, lines 65, 49 to switch 50. From this switch 50 extends line 51 to receive power from line 57 after the direction switches are thrown.

At this first position of the controller 15 as to the contact 16 being in connection with the terminal 46, the remote contact 26 is shifted to cover the terminal 53 in connection by line 54 through down limit car carried switch 55, thence by line 56 to power supply line 57.

In parallel with the switches 200, 50, at the speed responsive device 10, which switches 200, 50, are normally open at low speed, there is branch 62 from the line 201. This branch 62 extends to motor 59 which is a switch operating device of rotating field magnet type for effecting the operation of the direction switches. This line 62 in extending to this motor 59 is to winding 61 of a Y field with winding 60 having therefrom

line 58 extending to the line 31. This motor 59 has in addition to the windings 60, 61, a third winding 63 connected by line 64 to line 65 to resistance 66 thence by way of line 67 to terminal 68 adjacent the controller contact 16, thence by way of line 69 through lower limit switch 55 in the elevator car 3, thence by way of line 70 to terminal 71 as a second terminal adjacent this controller 15 to be engaged by the contact 26 at the second position of shifting and at the first real position of operation in the shifting of this controller 15. This position of the controller 15 in swinging the contact 26 to cover the contact 71 is such that the upper contact 16 does not cover any additional terminals. There is accordingly this intermediate position in the shifting of the controller 15 which position brings about the operation of the direction switches.

This operation of the direction switch throwing motor 59 starts the motor switch shaft 72 carrying cam 73 for throwing switch 74. With the direction switch 74 now shifted for down direction travel, it is to be borne in mind that the main switch operating device or motor 75 still idle, has its shaft 76 with cam 77 thereon holding normally closed low speed main switch 78. This main switch 78 accordingly is in position to connect the power supply line 45 with power supply line 79 which has branch 80 extending to slow speed accelerating switch motor 81. At said slow speed switch or rotary magnet device 81, this line 80 is connected to winding 82 having Y connection with winding 83, with line 84 from this motor 81 to power line 85 extending to the slow speed main switch 78 where it is there connected by this closed switch with the power supply line 52. This torque motor slow speed accelerating switch operating device 81 has a third winding 86 connected by line 87 extending to power line 88 connected by the closing of the down direction switch 74 with power supply line 25. Accordingly the three phases to this motor 81 are now energized and the shaft 89 of this motor 81 is rotated to drive pinion 90 in mesh with gear 91 for two to one speed reduction operation of the shaft 92, the cam 93 thereon throwing switch 94.

Inasmuch as the low speed main switch 78 is normally in or closed, this does not mean that the motor 8 is energized. Energizing of the motor 8 does not occur until the direction switch 74 is thrown. As this direction switch 74 is thrown, power supply line 57 is connected to power line 52 extending to low speed main switch 78 where this power line 52 is connected to power line 85. This line 85 extends to resistances 95, 96, 97, and thence by line 98 to winding 99 at the motor 8. This normally closed low speed main switch is accordingly normally

connected to power supply line 45 and thus connected by power line 79 extending to resistances 100, 101, 102, and thence by line 103 to second winding 104 of the slow speed windings of the motor 8. The closing of the direction switch 74 connects the power supply line 25 with the power line 88 extending to resistance 105 and thence by line 106 to third slow speed winding 107 at the motor 8. Accordingly at once the direction switch 74 is thrown in under the circumstances that the low speed main switch is also previously closed or normally closed there is energizing of slow speed windings 99, 104, 107, of the motor 8.

Simultaneously with the energizing of the three slow speed windings of the motor 8 due to the closing of the direction switch 74 and the energizing of the slow speed acceleration operating device 81, there is release of the brake at the drum 11. From the line 87 extends line 108 to switch 30 where it is connected by the closing of this switch 30 with the line 109 extending past brake coil resistance 110 and thence by line 111 to brake coil 112. From the direction switch having therefrom line 52 and line 51 there is branch line 113 connected by the closing of the switch 30 with line 114 through brake coil resistance 115 and thence by line 116 to the brake coil 117. From these brake coils 112, 117, extends line 118 to line 44 and thence to the power supply line 45. The shaft 9 is accordingly released and the motor is ready to start on its slow speed windings effecting driving of the elevator car 3 through the action of the rotation of the drum 5. Simultaneously the motor 81 starts to rotate the shaft 92 in effecting closing of the switch 94.

As this shaft 92 starts to rotate and in effecting first the closing of the switch 94, this switch effects the connecting of the power supply line 85 with line 119 to cut out resistance 95 and simultaneously connects power supply 79 to line 120 to cut out the resistance 100. The further rotation of this shaft 92 as driven by the motor 81 then effects through the cam 121 the operation of the switch 122, a time interval after the operation of the switch 94. This switch 122 by line 123 effects connection of the line 119 to the line 123 to by-pass resistance 96 and simultaneously through the line 120 connects line 124 to short out resistance 101. There is accordingly left in, as current flow modifying means, only the permanent resistances 97, 102, 105, in the slow speed windings 99, 104, 107, of the motor 8. These permanent resistances serve to cushion the stopping of the motor. At installation these resistances may be regulated to conform to the conditions desired in operation for such specific installation. This means that there is at hand a ready means for adapting to extreme

conditions with great nicety. In this operation the controller may be thrown at once to high speed for a smooth pickup while in shutting off the motor there is automatically 5 an introduction of the slow speed resistances for cushioning the stopping of the motor. These resistances are placed in the primary winding. Placing these resistances in the winding and increasing such resistances directly 10 decreases the torque.

In shifting the controller 15 further to the left for the high speed down direction travel of the elevator car 3, the contact 16 comes to the terminal 125 connected by way 15 of line 126 through the emergency switch 19 thence by line 127 to winding 128 of the main switch operating motor 75. Simultaneously this controller 15 has its contact 26 extend to terminal 129 thus connecting by 20 way of line 130 through the down limit switch 55 on the car 3 thence by line 131 to interlock 132 on up direction switch 133 which is closed because the operation of the shaft 72 has shifted the cam 73 and closed 25 the down direction switch 74. Accordingly with the switch 133 open and the interlock 132 closed, the line 131 is connected by line 134 to winding 135 of the switch operating motor 75. The third winding 136 for this 30 switch operating motor 75 is connected by line 137 to the line 31. This switch operating motor 75 is now energized and it shifts the cam 77 for opening the closed main switch 78 and through cam 138 effects closing 35 of high speed main switch 139.

This closing of the main high speed switch 139 through the action of the cam 138, it is noted, occurs simultaneously with the cutting out of the low speed windings of the motor 8 due to the opening of the main low speed switch 78. As this high speed main switch 139 is cut in, it connects the power line 52 with power line 140 extending to high speed winding 141 at the motor 8. Simultaneously this 40 high speed main switch 139 connects the power supply line 45 with line 142 extending to winding 143 at the motor 8. The down direction switch 74 has connected the power supply line 25 with the power supply line 88 and simultaneously it is effective in connecting the power supply line 57 with the power line 52. From power line 88 extends line 144 to the third high speed winding 145 at the motor 8.

The supply line 142 has branch 146 extending to high speed accelerating motor 147 where it is connected to winding 148 therefor. From the switch 139, line 140 has branch 149 extending to this high speed 45 accelerating switch motor 147 where the line 149 connects to winding 150. The power line 88 has branch 151 extending to the third winding 152 of this rotating field magnet or switch operating device 147 having shaft 153 carrying pinion 154 in mesh with two

to one speed reduction gear 155 for rotating shaft 156.

The winding 141 at the motor 8 has therefrom line 157 extending to resistances 158, 159, 160, 161. The winding 143 has extending from this motor 8 a line 162 extending by way of resistances 163, 164, 165, 166. The third winding 145 at this motor 8 has a line 167 extending therefrom, thence by way of resistances 168, 169, 170, 171. These series of 75 resistances are terminally connected by line 172. Accordingly these resistances are outside of the motor and the Y winding for this motor 8 for high speed operation has its junction exterior the motor with these resistances therein. Accordingly as the high speed main switch 139 is thrown in the high speed windings 141, 143, 145, are energized with considerable resistances in series with each thereof. The simultaneous energizing of the 80 motor 147 serves to operate the shaft 156 carrying cam 173 effective to operate in the first instance switch 174. This switch 174 through lines 175, 176, 177, is effective for cutting out the resistances 166, 161, 171. 90

As this shaft 156 in its rotation a little farther due to its cam 178 effects closing of switch 179, it thereby through lines 180, 181, 182, shorts out additional resistances 165, 160, 170. 95

At a still further rotation of this shaft 156, through cam 183, it then effects closing of the switch 184 and through lines 185, 186, 187, shorts out resistances 164, 159, 169.

In the final arc of travel of this shaft 156, through cam 188, thereon it effects closing of switch 189 and thereby connects directly lines 157, 162, 167, and cuts out the final and all of the resistances in the drawn out junction between the windings 141, 143, 145. The 100 final resistances thus cut out are 163, 158, 168.

The rate of rotation of this shaft 156 may be regulated through a dash pot mechanism. In the present embodiment thereof there is 110 mounted on the terminus of the shaft 156, a disk 190, from which extends a flexible connection 191 to counterweighted piston 192 extending into dash pot or cylinder 193, the leakage of which may be adjusted by means 115 of valve 194. On the disk 190, is disposed a projection, stop or lug 195, which, in the rotation of the shaft 156 in either direction thereof comes into stop relation with a fixed abutment 196. 120

The rotation of the accelerating shafts 156, 92, as herein provided may approximate 120° in each direction or a total of 240°. The cams for throwing the accelerating switches are bilaterally symmetrical so that the shifting of the switches occurs in the same sequence regardless of the direction of rotation of the shafts 92 or 156. 125

In the shorter arc rotation of the shafts 72, 76, there is a coupling with a pair of counter 130

weights 197, 198, which are to be overcome in the throw of 55° in each direction and these counterweights normally set the devices, as do the counterweights 193 for the shafts 92 and 156. These counterweights 197, 198, stop against fixed abutment 199.

It is to be noted that interlock 132 at the up direction switch 133 is always in when the down direction switch 74 is closed. Accordingly there may be no operation of the main switch operating motor 75 from low to high speed until after the direction switch is thrown for such desired direction of operation. This is a safety device precluding throwing of high speed connection in reverse direction.

Assuming that the high speed of rotation of the motor 8 is 1200 R. P. M. and that the low speed of rotation of this motor 8 is 300 R. P. M. The slow speed governor may be set at say 450 R. P. M. to close switch 50 as well as switch 200. Accordingly as long as the motor 8 is operating at about 450 R. P. M., the switches as controlled by the fly-ball governor 10 are closed and at lower speeds are opened.

As long as the controller 15 is in position for driving the motor 8 through its high speed winding, the operation of the motor 30 will be entirely independent of the position of the switches 50 and 200. After the motor 8 has reached a speed sufficient to cause the governor 10 to close these switches, however, and the controller is then returned to neutral 35 position, the direction motor 59 will still be held in as long as the switches 50 and 200 remain closed.

With the controller 15 at neutral position, the high speed main switch 139 is open and 40 the low speed switch 78 is closed. This holding in of the direction motor 59 is effected by the switch 50 held closed by the governor 10 for connecting the lines 49 and 51 to the windings 61 of the motor 59. The switch 200 45 is held closed by the governor 10 through lines 201, 202, and serves to connect the line 64 to the winding 63 of this direction motor 59. The third winding 60 on this direction motor 59 is connected by the line 58 through the 50 door interlocks and the safety devices, thence by line 44 to the power supply line 45. Accordingly as long as the speed of the motor 8 is above the rate of speed for the opening of the switches 50 and 200 on the governor 55 10, there is a holding in of the windings 99, 104, 107, of the slow speed windings of the motor 8 together with the permanent resistances 92, 97, 105, in series therewith. There is thus a generator load upon this motor 8 60 to act as an electric brake in retarding or slowing up the speed of the shaft 9.

Furthermore in the embodiment as herein disclosed, this generator braking action as brought about through the position of the 65 governor 10 in maintaining closed the

switches 50, 200, may occur automatically at a time before the setting of the brake upon the drum 11 if the controller 15 is off center sufficiently for the contact 26 to reach the terminal 53. In such event the switches 30 70 are held closed and current is provided for the coils 112, 117. As soon as the governor 10 opens the switches 50 and 200 the direction motor is deenergized and with the contact 16 of the controller 15 off the terminal 75 46, the brake coils are also deenergized and the brake is effective in gripping the drum 11. This is a material factor in lengthening the life of the brake shoes of the drum as well as a material factor in smoothing the 80 slowing down of the elevator car 3.

In the operation of the controller 15 for up direction travel of the car 3, the controller, of course, is shifted oppositely to that hereinbefore described for down direction 85 travel. Similar current connections for such opposite way of travel are effected but instead of being through the down limit switch 55 on the car 3, such are through upper limit switch 203 on the car 3. 90

The resistances 48, 66 have peculiar value as safety features in the combination herein disclosed. One of these features is that of an interlock, which interlock is of an electrical nature instead of a mechanical character. 95 In reversible motor operation, more particularly in elevator practice, many times the operator instead of pulling the controller 15 to center will pull it past center for reversal. In the combination herewith, the speed governor 10 holding the direction switch in, operates upon the reversal of the controller 15 to permit current flow by way of lines 47 or 67 having the resistances 48, 66. These resistances are of such strength as to keep 105 down any excessive or large amount of current flow which might arise from a shorting between phases due to the reversal of the controller as described. This means there is no excessive heating due to the reversal of 110 the controller when the elevator car 3 is under way so that the governor 10 is in for assisting in stopping the elevator by the generator action, beyond its synchronous speed. 115

There is a further safety feature due to 115 these resistances 48, 66. In the event that the control governor should become stuck or the circuit of this governor switch in any manner be shorted or remain closed, these resistances 48, 66 are in parallel with the 120 windings to the direction motor and slow speed windings of the elevator motor. Due to the very low impedance of the primary windings of the elevator motor, there is not enough current passing to the direction 125 motor or control torque motor 59 to be effective in operating this motor because the resistances 48, 66 are relatively so high.

What is claimed and it is desired to secure by Letters Patent is:

1. A motor, a high speed winding therefor, a low speed winding therefor, acceleration resistances in series with the low speed winding, a normally closed low speed main switch, a direction switch for cutting in power current to the low speed winding through said main switch, a permanent resistance in series with the low speed winding for cushioning the stopping of the motor, switches for cutting out the acceleration resistances, and a controller for the switches.
2. A reversible alternating current motor having a high speed winding and a low speed winding, a normally closed low speed main switch, a direction switch for cutting in power current to the low speed winding through said main switch, and a permanent resistor in series between said main switch and said motor.
3. A reversible alternating current motor having a high speed winding and a low speed winding, a normally closed low speed main switch, a direction switch for cutting in power current to the low speed winding through said main switch, and a permanent resistor in series with the power circuit.
4. A reversible alternating current motor having high speed connections and low speed connections, a normally closed low speed main switch, a direction switch for cutting in power current through said main switch to the low speed connections, and a permanent resistor in series with the low speed power circuit.
5. An alternating current motor having a high speed winding and a low speed winding, a normally closed low speed main switch, and a permanent resistor in series between said main switch and said motor.
6. An alternating current motor having a high speed winding and a low speed winding, a normally closed low speed main switch, and a permanent resistor in series with the power circuit.
7. An alternating current motor having high speed connection and low speed connections, a normally closed low speed main switch, and a permanent resistor in series with the low speed power circuit.
8. A reversible alternating current motor having high speed connections and low speed connections, a normally closed low speed main switch, a direction switch, a controller, and gravity operated means for establishing and other automatic means for maintaining a low speed power connection when, with the motor operating at high speed, the controller is shifted to any other position.
9. A reversible alternating current motor having high speed connections and low speed connections, a switch for each of said connections, the switch for the low speed connection being normally closed, a controller, and a speed responsive device for maintaining a circuit through a low speed connection, when the controller is shifted from motor actuating position to stopping position.
10. A reversible alternating current motor having high speed connections and low speed connections, a switch for each of said connections, the switch for the low speed connection being normally closed, a controller, and a speed responsive device for maintaining a circuit through a low speed connection when, with the motor operating at high speed, the controller is shifted to any other position.
11. A reversible alternating current motor having high speed connections and low speed connections, a normally closed low speed switch, a direction switch, a controller, permanent current flow modifying means in the low speed power circuit, and means automatically maintaining a low speed power connection when, with the motor operating at high speed, the controller is shifted to any other position.
12. A reversible alternating current motor having high speed connections and low speed connections, a switch for each of said connections, the switch for the low speed connections being normally closed, a controller, permanent current flow modifying means in the low speed power circuit, and a speed responsive device for maintaining a circuit through a low speed connection when the controller is shifted from motor actuating position to stopping position.
13. A reversible alternating current motor having high speed connections and low speed connections, a switch for each of said connections, the switch for the low speed connections being normally closed, a controller, permanent current flow modifying means in the low speed power circuit, and a speed responsive device for maintaining a low speed connection when, with the motor operating at a high speed, the controller is shifted to any other position.
14. A motor, a high speed winding therefor, a low speed winding therefor, permanent and acceleration resistances for the low speed winding, a normally closed low speed main switch with said permanent resistance in series between said switch and the motor, a direction switch for cutting in power current to the low speed winding through said main switch, switches for cutting out the acceleration resistance, rotating field magnets for throwing the switches, and a controller for the magnets.
15. A motor, a high speed winding therefor, a low speed winding therefor, resistance for said low speed winding, switches for the windings, a controller for the switches, a brake for the motor, and automatic means for holding the low speed winding and its resistance in and additionally setting the brake with the controller in off position.
16. A reversible alternating current motor,

- 6
- direction switches for the motor, a rotary actuator for the direction switches, a controller for said actuator and means precluding the shifting of said actuator by a reversal of the controller while the motor is operating above a predetermined speed. 17. A reversible alternating current motor, direction switches for the motor, a polyphase rotary actuator for the direction switches, a polyphase controller for said actuator, and means precluding the shifting of said actuator by a reversal of the controller while the motor is operating above a predetermined speed. 18. A two-speed reversible alternating current motor, main and direction switches therefor, a polyphase rotary actuator for the direction switches, a polyphase controller for said actuator, and means precluding the shifting of said actuator by a reversal of the controller while the motor is operating above a predetermined speed. 19. A reversible alternating current motor, direction switches for the motor, a polyphase rotary actuator for the direction switches, a polyphase controller for said actuator, speed responsive means precluding the shifting of said actuator by a reversal of the controller while the motor is operating above a predetermined speed, and resistance means in the controller circuit precluding the short circuiting of the same under such conditions. 20. A reversible alternating current motor having high speed connections and low speed connections, switches for said connections, direction switches for the motor, a polyphase rotary actuator for the direction switches, a polyphase controller for said actuator, speed responsive means precluding the shifting of said actuator by a reversal of the controller while the motor is operating above a predetermined speed, and resistance means in the controller circuit precluding the short circuiting of the same under such conditions. 21. A motor, a power current supply for the motor, a high speed winding for the motor, a low speed winding for the motor, a plurality of acceleration resistances in series with the low speed winding, a plurality of acceleration resistances in series with the high speed winding, switches for the acceleration resistances, high and low speed main switches, direction switches, four rotating field magnets for operating said switches, and a controller for determining the sequence of operation of said magnets, said acceleration switch operating magnets being energized by the power current supply only as supplied to the motor, and the respective windings and their respective resistances being in parallel with the respective magnets. 22. A motor, a high speed winding therefor, a low speed winding therefor, separate acceleration resistances for said windings, switches for the respective acceleration resistances, a normally closed main switch for the low speed winding, a main switch for the high speed winding, direction switch means for connecting the low speed winding through the low speed main switch for operating the motor at low speed, separate power means as operators for the respective acceleration resistance switches, power means for the direction switch means, means for closing the high speed main switch coacting simultaneously for opening the low speed main switch, and a controller effective through said last-mentioned means for directly operating said low and high speed switches. 23. A reversible motor, a high speed winding therefor, a low speed winding therefor, a normally closed main switch for the low speed winding, an additional main switch for the high speed winding, direction switch means, a main switch operating device for both of said switches, an interlock controlled by the direction switch means, and a controller rendered by said interlock, ineffective for supplying power current to the motor by way of the high speed main switch, when the controller is shifted from a position for operation of the motor in one direction to a position for operation of the motor in the other direction, until the direction switch means is operated. 24. A polyphase reversible motor, a high speed winding therefor, a low speed primary winding therefor, permanent torque decreasing means for said low speed winding, switches for the windings, a polyphase controller for the switches, and a speed responsive device for holding the low speed winding and its permanent torque decreasing means in circuit, with the controller shifted back from a position for low speed operation of the motor in a given direction, as long as the motor is still operated in that direction above a predetermined speed. 25. A motor, a high speed winding therefor, a low speed winding therefor, resistance for said low speed winding, a normally closed main switch for the low speed winding, an additional switch for the high speed windings, operating means for the switches, a controller directly effective by operating the switch operating means at all times, and automatic means for holding the low speed winding and its resistance in circuit. 26. A motor, a high speed winding therefor, a low speed winding therefor, resistance for said low speed winding, a normally closed main switch for the low speed winding, an additional switch for the high speed windings, a controller for the switches, a brake for the motor, and automatic means for holding the low speed winding and its resistance in circuit and additionally setting the brake with the controller in off position. 27. The combination with an elevator, of a

- multi-speed polyphase electric motor therefor having primary windings, acceleration resistances in series with said windings, main, direction, and acceleration switches 6 for the motor, rotating field magnets for operating the switches, a power line for the magnets, a controller for the rotating field magnets, whereby the selection and sequence of switch opening and closing is determined, 10 one of said switches being closed with the controller in off position, and two other lines for the magnets having operative connection thereof determined by said controller.
28. The combination with an elevator, of 15 a multi-speed polyphase electric motor therefor having primary windings, acceleration resistances in series with said windings, sets of main, direction and acceleration switches for the motor, a rotating field magnet for 20 operating each set, a controller for the rotating field magnets, whereby the selection and sequence of switch opening and closing is determined, one of said switches being closed with the controller in off position, and an 25 interlock precluding the rendering of the controller effective for operating a high speed switch, if said controller is shifted from a position for operation of the motor in one direction to a position for operation of the 30 motor in the other direction, when the motor is operating.
29. An elevator control system having a multi-speed polyphase electric motor provided with a primary winding having a Y- 35 junction brought out of the motor, a polyphase electric current supply for the motor, said system embodying acceleration resistances between said junction and the windings, a main switch, acceleration switches, a 40 torque motor for operating the main switch, a torque motor for operating the acceleration switches, and a controller for said motors, establishing operating connection for the acceleration torque motor, to be completed 45 by the operation of the main switch of the other torque motor, said acceleration switch torque motor being operable by said controller only when all phases of the current are supplied to the power motor.
30. A control system comprising a polyphase electric motor provided with a primary winding having a permanently closed Y-junction brought out of the motor, a polyphase electric current supply for the motor, 50 said system embodying acceleration resistance between the junction and the winding, switch means for said winding remote from the junction, switches for the acceleration resistance, and separate power actuated devices for the acceleration switches connected 55 on the same side as said motor, said devices for operating the acceleration switches being operable by the controller only when all 60 phases of the current are supplied to the power motor.
31. A control system having a polyphase electric motor provided with a primary winding having a permanently closed Y-junction brought out of the motor, said system embodying acceleration resistance between the junction and each winding, sets of switches for cutting out said resistances in sequence, an additional switch for the motor, and separate power actuated devices for said sets of switches, said devices 70 being on the same side of said additional switch as said motor.
32. A reversible motor, direction switches for the motor, a common reversible actuator for the direction switches, a controller for 80 said actuator, means by-passing the controller and effective to temporarily maintain the position of the actuator, and resistance means in the controller circuit, rendering said controller ineffective to reverse said actuator while the by-passing means is effective.
33. A reversible alternating current motor, direction switches for the motor, a common reversible polyphase actuator for the 85 direction switches, a polyphase controller for said actuator, means by-passing the controller and effective to temporarily maintain the position of the actuator after the controller has been moved to shift said actuator, and resistance means in two phases of the controller circuit, rendering said controller ineffective to reverse said actuator while the by-passing means is effective.
34. A reversible motor, direction switches 90 for the motor, a common reversible actuator for the direction switches, a controller for said actuator, speed responsive means bypassing the controller and effective to maintain the position of the actuator until the 95 motor has slowed down after the controller has been moved to shift said actuator while the by-passing means is effective.
35. A motor control installation including 100 direction switches, conductor lines to said switches for polyphase electric current, a direction switch operating motor, a controller for the motor, a speed responsive device for holding the direction switch in, and supplemental control means including 105 resistances between the controller and switch operating means precluding excessive current flow arising from shorting between different phase conductor lines when the controller is reversed.
36. A main motor, a direction switch therefor, a direction switch operating motor, a controller for the direction switch motor, a speed responsive device for holding the direction switch in independently of the 115 controller, and supplemental control means including resistance between said controller and the direction switch operating motor and connections on the same side of said switch as the main motor for precluding 120
- 125
- 130

- operation of the direction motor when the speed of the main motor is great enough to actuate said speed responsive device.
37. A polyphase motor control installation including conductor lines for different phases of electric current, a speed responsive device provided with a switch, a direction switch for the motor, a multi-phase actuating device for the direction switch, and connections from a plurality of conductor lines for different phases to said speed responsive device switch and said actuating device, said actuating device being connected on the same side of the direction switch as the motor.
38. A multi-speed motor provided with high and low speed primary windings, switches for the windings, a controller for the switches, conductor lines for different phases of electric current, multi-phase actuating means for the switches, and a speed responsive device for holding in the low speed windings, when the controller is shifted to stop the motor, while the motor acts as a generator and electric brake, until said motor approaches synchronous speed, said device including switches in a plurality of said conductor lines for different phases connected to said actuating means.
39. A multi-speed motor provided with
- high and low speed primary windings, conductor lines for different phases of electric current, a torque decreasing permanent resistor in series with said low speed windings, switches for the windings, a controller for the switches, and a speed responsive device for holding in the low speed windings and said resistor, when the controller is shifted to stop the motor, while the motor acts as a generator and electric brake, until said motor approaches synchronous speed, said device including switches in a plurality of said conductor lines for different phases.
40. An alternating current power motor having high and low speed connections, polyphase supply lines therefor, a line switch for said motor, a resistor for each speed, a set of acceleration switches for each resistor, means including a torque motor and rock shaft for operating the line switch, similar operating means for each set of acceleration switches, control means for the line switch torque motor, and means for energizing the torque motors for the acceleration switches only when all phases of the current are supplied to the power motor.

In witness whereof I affix my signature.

ERNEST B. THURSTON.
